(57) CLAIM

The ornamental design for a clip for hanging garments, as shown and described.

DESCRIPTION

FIG. 1 is a top plan view showing my new design for a clip for hanging garments;

FIG. 2 is a front elevational view thereof;

FIG. 3 is a right side elevational view thereof, the left side elevational view being identical thereof;

FIG. 4 is a bottom plan view thereof; and,

FIG. 5 is a reduced view in perspective showing the clip in use hanging garments which are shown in broken lines for illustrative purposes only forming no part of the claimed design.
